TRANSPARENT SUPPORTING CHANNEL FOR LIGHTING FIXTURE PANELS

Kurt Franck, Newark, Ohio, assignor to Holophane Company, Inc., New York, N.Y., a corporation of Delaware

Filed June 12, 1957, Ser. No. 46,562

Term of patent 14 years

(Cl. D13—1)

Fig. 1 is a bottom perspective view of a transparent supporting channel for lighting fixture panels showing my new design, with the panel in broken lines being shown for illustrative purposes only;

Fig. 2 is a fragmentary top perspective view thereof; and

Fig. 3 is an end view thereof.

I claim:

The ornamental design for a transparent supporting channel for lighting fixture panels, as shown,
